UNITED STATES PATENT OFFICE.

OSCAR I. JUDELSHON, OF BROOKLYN, NEW YORK.

CLOTH-CUTTING MACHINE.

1,242,448.

Specification of Letters Patent.

Patented Oct. 9, 1917.

Application filed August 5, 1916. Serial No. 113,242.

To all whom it may concern:

Be it known that I, OSCAR I. JUDELSHON, a citizen of the United States, and resident of New York city, borough of Brooklyn, in the county of Kings and State of New York, have invented certain new and useful Improvements in Cloth-Cutting Machines, of which the following is a specification.

The object of my invention is to provide means to cut rolls of cloth, paper and analogous webs into spools or reels of desired width, such rolls usually being wound upon hollow cores, such as upon a paper or pasteboard tube.

My invention comprises novel details of improvement and combinations of parts that will be more fully hereinafter set forth and then pointed out in the claims.

Reference is to be had to the accompanying drawings forming part hereof, wherein,

Figure 1 is a partly broken plan view of a machine embodying my invention;

Fig. 1^a is a sectional detail of part of the means for rotating the roll to be cut into spools;

Fig. 2 is a partly broken side view of a portion of Fig. 1;

Fig. 3 is a section on the line 3, 3, in Fig. 2;

Fig. 4 is an end view, looking at the right hand side of Fig. 1;

Fig. 5 is an enlarged sectional detail through the roll rotating means;

Fig. 6 is an enlarged detail section illustrating the cutter during operation of cutting the roll;

Fig. 7 is an enlarged detail plan view, partly in section, illustrating means for adjusting the cutter grinding wheel;

Fig. 8 is a section on the line 8, 8, in Fig. 7; and Fig. 9 is a detail section illustrating means for supporting a grinder adjacent the cutter hereinafter referred to.

In the accompanying drawings the numeral 1 indicates a suitable frame, upon which spaced uprights or brackets 2 are secured, in which uprights shaft 3 is supported to rotate in suitable bearings, and a non-rotative rod 4 parallel with shaft 3 is secured to said uprights. Above rod 4 a non-rotative rod 5 is supported by the uprights 2, adapted to support a roll 6 of cloth or other article to be severed. Rod 5 may be secured in an opening or bearing in one of the uprights 2, by a set screw 7 (Fig. 5), and

at the opposite end of said rod is a supporting arm 8 having an opening or recess receiving the adjacent end of the rod. Arm 8 is slidably mounted upon rod 4 and a bolt or screw 9 is adapted to detachably retain arm 8 in set position on the adjacent upright or bracket 2. The arrangement is such that arm 8 may be released from bolt or stud 9 to permit the arm to be slid outwardly along rod 4 to release rod 5, whereupon said arm may be swung to one side to permit the application of roll 6 to or its removal from rod 5. When arm 8 is secured in position to support rod 5 the latter will be held from movement in any direction while the roll 6 rotates on said rod. The roll 6 is illustrated of a character having a tubular core 6^a, as of paper, pasteboard or the like, upon which the fabric web is wound. Means are provided for rotating roll 6 around rod 5 when the roll is to be cut. For such purpose I have shown a sleeve 10 mounted to rotate upon rod 5 and provided with a head 10^a provided with pins 16 adapted to enter the material of roll 6. Said pins are shown carried on arm 17 projecting from slides 18 located in grooves 10^b in the adjacent face of head 10^a, screws 19 threaded in said head serving to jam against slides 18 to retain them in set position on the head. By this means the slides may be adjusted radially to provide for rolls 6 of different diameter, the pins may be entered in the rolls and the slides 18 set tight in the head, whereby when sleeve 10 is rotated the roll will be correspondingly rotated thereby on rod 5. Sleeve 10 is shown provided with a sprocket wheel 11 receiving chain 12 from a sprocket wheel 13 secured on shaft 3, which shaft is shown provided with fast and loose pulleys 14, 15 adapted to receive a belt for rotating said shaft, sleeve 10 and the roll.

In order to cut the rolls transversely at suitable distances therealong, to produce from the rolls spools or reels of suitable width, I provide a rotary cutter 20, suitably spaced from rod 5 and shown located at right angles thereto, the cutter being adapted to move toward the reel and rod and away therefrom. Said cutter is shown mounted upon shaft 21 which is journaled in bearings on an arm 22 that is mounted to rock upon shaft 3. Cutter 20 may be detachably held upon shaft 21 by means of

a nut serving to clamp the cutter against a stop or flange on the shaft in an ordinary manner. The means I have shown to rotate cutter 20 comprise a sprocket wheel 23 secured on shaft 21 and receiving a chain 24 passing from a sprocket wheel 25 slidably mounted on shaft 3, said shaft 3 being shown provided with a longitudinal groove 3^a receiving a key or stud projecting from the sprocket wheel, whereby the cutter may be rotated in its different positions of adjustment along shaft 3 relatively to roll 6. By means of a suitably shaped arm 26 secured to arm 22, the latter may be rocked 15 to cause the cutter to approach and recede from the roll. The cutter is normally retained retracted from roll 6, for which purpose I have shown a spring 27 connecting arm 22 with a member on a slide or table 28. To limit the rearward movement of arm 22 by spring 27 I provide a stop 29, shown in the form of a screw working in a threaded opening in an upright 30 on slide or table 28, a nut 31 on said screw serving 20 to retain the same in set position. To limit the movement of the cutter toward rod 5 I provide a stop 32, shown in the form of a screw working in a threaded opening in an upright 33 on said slide or table. The 25 screw may be held in set position by a nut 34. The stop-screws 29 and 32 are adapted to be adjusted to accommodate cutters of different diameters so that when a cutter is worn away by sharpening or grinding, stop-screw 32 may be set to permit the cutting edge to approach nearer to rod 5 as may be required to cut the roll and its tube 6^a. Slide or table 28 is adjustable along the 30 frame below roll 6, and is provided with an opening receiving arm 22 whereby the latter will be moved along said shaft with the slide or table. Said slide or table is shown slidably receiving shaft 3 and rod 4, whereby the table is guided, and in order to relieve shaft 3 from the weight of the table and its parts I have shown said table provided with a forked arm 36 in which a roller 35 is journaled and adapted to travel upon a plate or rail 37 secured on frame 1. In 35 order to move the table and cutter along the frame relative to roll 6 as desired, I provide a hand wheel 38 journaled upon the frame, as upon a stud or shaft 39 secured thereon. To said wheel is connected a sprocket wheel 40 engaging a chain 41 that is stretched along the frame between the end brackets 2, as by securing the ends of the chain to suitable stops 42 on said brackets, as by means of screws 43. The foregoing provides a simple and efficient means for 45 enabling adjustment of the table and cutter along the frame in either direction as desired, although other suitable means for such purpose may be provided.

60 Since the cutter 20 may become dull during

use, I provide means for grinding the cutting edge thereof as desired, or as the cutter rotates. For such purpose I have shown a rotary grinder or emery wheel 44 secured upon shaft 45, that is journaled in bearings 70 on a standard or upright 46 carried by table 28. Said upright is adjustably mounted upon said table, whereby the emery wheel may be adjusted to desired positions. I have shown the standard or upright 46 75 as provided with a foot or extension 47 adjustable upon a plate 48 which in turn is adjustable upon table 28. The plate 48 is shown slotted at 49 to receive screws 50, threaded in apertures in table 28, (Figs. 1, 80 7 and 8), whereby plate 48 may be set in different positions for the desired adjustment of the emery wheel with respect to the cutting edge of cutter 20. Since the cutting edge of said cutter is preferably beveled, I have shown plate 48 set at an angle to table 28, whereby the emery wheel is correspondingly located at an angle with respect to the cutter, and as the cutter becomes reduced in diameter the emery wheel 85 may be adjusted as required with relation to the cutting edge. In order to permit the emery wheel to be adjusted angularly with respect to the cutter, I have shown the foot 47 as mounted upon screws 51 entering 90 threaded lugs 52 on table 28 at opposite ends of said foot, whereby the latter may be set at different angles with respect to table 28, to correspondingly tilt the emery wheel. Screws 53, located in threaded apertures in 95 foot 47 on opposite sides of a line passing through screws 51 and adapted respectively to bear upon plate 48, serve to retain said plate in set position, whereby the emery wheel may be set and retained at a desired 100 angle with respect to the cutter, so that the face of the emery wheel at one side of its axis only will engage the cutting edge of the cutter. Nuts 54 on screws 53 serve to retain said screws in set position. By the 105 means described the emery wheel and cutter may be moved together along the frame with respect to roll 6 as table 28 is moved along the main frame.

In order to rotate the grinder or emery wheel 44 I have shown a pulley 55 secured upon shaft 45 and receiving a belt 56 that passes over a pulley 57 driven by shaft 3, as by being secured to sprocket 25, or provided with a key entering groove 3^a, of 115 shaft 3, whereby the latter shaft rotates said pulley. Said belt is also shown passing over a pulley 58 journaled upon a suitable support on table 28. Since there are three pulleys angularly disposed receiving 120 belt 56, the latter will properly rotate the grinder or emery wheel in any position of adjustment of the latter. In order to finish or smooth the side of the cutter 20 opposite its beveled edge or face, as acted upon by 125 130

the grinder or emery wheel 44, I provide a smoothing stone or emery block 59 shown journaled in a clamping device 60 supported upon table 28. Said clamping device is 5 shown comprising a bar or the like 61 and a clamping plate 62 secured thereto by screw 63, the opposing faces of said bar and clamping plate being shown curved in the nature of a clamp to grip the stone or 10 emery block 59. (See Fig. 9). An upright 64 is secured upon table 28, and is provided with a flat head 65 upon which bar 61 rests, said bar being shown longitudinally slotted at 61^a to receive a screw 66 working in a 15 threaded aperture in head 65, whereby bar 61 may be adjusted for adjustment of stone or emery 60 along the face of cutter 20. By means of screw 68 (Figs. 1 and 2), working in threaded apertures in head 65 and 20 bearing against bar 61, the latter may be retained in set position annularly with respect to the face of cutter 20, to retain the stone or emery 59 at a desired angle with the face of the cutter. The stone or emery 25 59 may be longitudinally adjusted in the clamp 60, 62 with respect to the face of cutter 20, as may be required, owing to wearing away of the working end of the stone or emery or the adjacent face of the cutter. 30 By means of the arrangements described with regard to the grinder and emery it will be understood that when the cutter is moved back from roll 6 the grinding wheel or emery 44 will serve to sharpen the rotating 35 cutter, and at the same time the stone or emery 59 will smooth the opposite face of the cutting edge, and when the cutter is moved to the roll the sharpening of the cutter will be discontinued.

40 Since the rolls to be cut into spools or reels in the example illustrated comprise webs of cloth, paper or other fabric wound upon the tubular core 6, and since such core is to be cut or severed through for the 45 spools or reels, and as the cutter is to be adjusted, step by step, along the roll a distance equal to the width of each spool to be cut, I have shown rod 5 as grooved at 5^a longitudinally on the side opposing the cutter (Figs. 3 and 6) in such manner that the cutting edge of the cutter may pass through the tube or core 6^a and partly into said 50 groove in all positions of the cutter along rod 5, without cutting the rod. The stop 55 32 may be set to engage arm 22 to limit the advance of the cutter toward rod 5 and into its groove, so that the cutter may sever the material of the rotating roll and the tube or core 6^a in accordance with the 60 diameter thereof.

When the spools or reels are to be cut from the roll of fabric, it is merely necessary to move the arm 8 outwardly, swing it to one side free from rod 5, slide the roll 65 upon said rod, replace arm 8 in connection

with rod 5, connect the roll with the head 10^a, and start the machine for rotation of the roll on the stationary rod 5. The operator may then operate wheel 38 to move table 28 and cutter 20 to bring the cutter to the 70 desired position along the roll. A scale indicated at 92 (Figs. 1 and 3) carried by table 28 and suitably located with respect to the plane of cutter 20, enables the operator to determine the distance of the point 75 (from the adjacent end of the roll) at which the cutter should be located to cut off the desired width of spool or reel from the roll. Arm 26 then may be depressed, causing the 80 rotating cutter to be moved against the roll to sever the latter, the stop 32, as before explained, preventing the cutter advancing too far toward rod 5 but sufficiently far to cut through the tube or core 6^a. The cutter then may be moved back from the roll, and 85 wheel 38 may be rotated to advance the cutter along the roll the desired distance for cutting off another spool or reel, such operations being repeated for as many spools or reels as are to be cut from the roll.

An advantage of my improvements is that 90 rod 5 is rigidly supported at both ends, so that the roll that rotates on the rod will have little, if any, vibration, and will resist the thrust or pressure of the cutter, thereby 95 enabling the spools or reels of fabric to be cut from the roll accurately and smoothly. Another advantage is that the length of the rod upon which the rolls are mounted may be relatively short, since the rolls are not 100 required to be fed along the rod for each cutting operation, since the cutter is to be moved relatively to the roll. This arrangement enables reduction in the dimensions of the machine, hence in the cost thereof, over 105 cloth roll cutting machines in which the roll is fed along its supporting shaft relatively to the cutter. My improvements enable also the production of a more rigid, economical and expeditiously operating machine.

110 While I have described my invention as adapted to cut rolls of fabric wound upon a hollow tube or core, it will be understood that the machine may be used to cut other material rotative upon a stationary rod, and the cutter may have a smooth or toothed cutting edge as desired.

115 My invention is not limited to the details of construction and arrangements of parts set forth, as the same may be varied, within 120 the scope of the appended claims, without departing from the spirit of the invention.

Having now described my invention what I claim is:—

125 1. A cutting machine comprising a frame, a rod having a longitudinal groove in one side, means to non-rotatively support the rod in the frame, means to rotate an article upon said rod, means to support a cutter at one side of the rod opposing the groove of 130

- the rod, said cutter arranged to enter the groove, and means to move the cutter relatively to the rod.
2. A cutting machine comprising a frame, 5 a rod having a longitudinal groove in one side, means to non-rotatively support the rod in the frame, means to rotate an article upon said rod, means to support a cutter at one side of the rod opposing the groove of the rod, said cutter arranged to enter the groove, means to move the cutter toward and from the rod, and means to move the cutter along the rod.
3. A cutting machine comprising a frame, 15 a rod having a longitudinal groove in one side, means to non-rotatively support the rod in the frame, means to rotate an article upon said rod, a table, means to movably support the table upon the frame, a cutter opposed to the groove in the rod, said cutter arranged to enter the groove, means to support and rotate the cutter upon the table, and means to permit the cutter to be moved toward and from the rod.
- 25 4. A cutting machine comprising a frame, a rod having a longitudinal groove in one side, means to non-rotatively support the rod in the frame, means to rotate an article upon said rod, a table, means to movably support the table upon the frame, a cutter opposed to the groove in the shaft, said cutter arranged to enter the groove, means to movably support the cutter upon the table for movement toward and from the rod, a 30 shaft, means to rotate the cutter by the shaft, and means to move the table along said rod and shaft.
5. A cutting machine comprising a frame, a stationary rod having a longitudinal 40 groove, means to support the rod in the frame, a head rotatively mounted on the rod and having means to connect with an article to be rotated by the head on the rod, a table, means to movably support the table upon the frame, a cutter, adapted to enter the groove in the rod, means to movably support the cutter upon the table for movement toward and from the rod, a shaft, means to rotate the cutter by the shaft, means to move the 45 table along said rod and shaft, and means connecting the shaft with said head for rotating the latter with the former.
6. A cutting machine comprising a frame, a rod, means to support the rod in the frame, 55 means rotative on the rod to rotate an article upon the rod, a table, means to slidably support the table upon the frame, a chain carried by the frame, a wheel carried by the table engaging the chain for moving the 60 table along the frame, a cutter opposed to the rod, means to support the cutter upon the frame for movement toward and from the rod, and means to rotate the cutter in different positions of adjustment along the 65 rod.
7. A cutting machine comprising a frame, means to support and rotate an article to be cut, a table, means to guide the table upon the frame, a cutter, means to rotatively support the cutter upon the table, means to rotate said cutter, a grinder, means pivotally supporting the grinder upon the table, means to rotate the grinder, means to adjust the grinder upon the table relatively to the cutter, and means to move the cutter away from the grinder toward said article. 75
8. A cutting machine comprising a frame, means to support and rotate an article to be cut, a table, means to guide the table upon the frame, a cutter, means to rotatively support the cutter upon the table, means to rotate said cutter, a grinder, a plate adjustably carried by the table, means pivotally supporting the grinder upon said plate, and means to rotate the grinder. 80
9. A cutting machine comprising a frame, means to support and rotate an article to be cut, a table, means to guide the table upon the frame, a cutter, means to rotatively support the cutter upon the table, means to rotate said cutter, a grinder, a plate adjustably carried by the table, an upright rotatively supporting the grinder, means to adjustably support said upright upon the plate, and means to rotate the grinder. 85
10. A cutting machine comprising a frame, means to support and rotate an article to be cut, a table, means to guide the table upon the frame, a cutter, means to rotatively support the cutter upon the table, means to rotate said cutter, a grinder, a plate upon the table, an upright rotatively supporting the grinder and having a foot, means pivotally supporting said foot upon said plate, means to retain said foot in set position, and means to rotate said grinder. 90
11. A cutting machine comprising a frame, means to support and rotate an article to be cut, a table, means to guide the table upon the frame, a cutter, means to rotatively support the cutter upon the table, means to rotate said cutter, a grinder adapted to act on one side of the cutter, means pivotally supporting the grinder upon the table, means to rotate the grinder, means to adjust the 115 grinder on the table relatively to the cutter, an emery at the opposite side of the cutter, and means upon said table for adjustably supporting said emery relatively to the cutter. 110
12. A cutting machine comprising a frame, means to support and rotate an article to be cut, a table, means to guide the table upon the frame, a cutter, means to rotatively support the cutter upon the table, means to rotate said cutter, a grinder adapted to act on one side of the cutter, means pivotally supporting the grinder upon the table, means to rotate the grinder, means to adjust the 125 grinder on the table relatively to the cutter, 120
13. A cutting machine comprising a frame, means to support and rotate an article to be cut, a table, means to guide the table upon the frame, a cutter, means to rotatively support the cutter upon the table, means to rotate said cutter, a grinder adapted to act on one side of the cutter, means pivotally supporting the grinder upon the table, means to rotate the grinder, means to adjust the 130 grinder on the table relatively to the cutter, 125

- an emery at the opposite side of the cutter, an upright upon the table, and a clamp for said emery adjustably carried by the upright to permit adjustment of the emery along the cutter.
13. A cutting machine comprising a frame, means to support and rotate an article to be cut, a table, means to guide the table upon the frame, a cutter, means to rotatively support the cutter upon the table, means to rotate said cutter, a grinder adapted to act on one side of the cutter, means pivotally supporting the grinder upon the table, means to rotate the grinder, means to adjust the grinder on the table relatively to the cutter,
- an emery at the opposite side of the cutter, an upright upon the table, a clamp for said emery adjustably carried by the upright to permit adjustment of the emery along the cutter, and means to adjust the emery relatively to the plane of the cutter and retain the emery in adjusted position. 20
- Signed at New York city, in the county of New York and State of New York, this 4th day of August, A. D. 1916.
